INSULATED BUCKET FOR ICE OR THE LIKE

David W. Darr, 2727 Spring Garden Road,
Winston-Salem, N.C. 27106

Filed Oct. 15, 1970, Ser. No. 25,497

Term of patent 14 years

Int. Cl. D7—02

U.S. Cl. D44—1

FIG. 2

FIG. 1

FIG. 4

FIG. 3

FIG. 1 is a side elevational view of an insulated bucket for ice or the like showing my new design;

FIG. 2 is a top plan view thereof;

FIG. 3 is a bottom plan view thereof; and

FIG. 4 is an enlarged section thereof taken on line 4—4 of FIG. 2.

I claim:

The ornamental design for an insulated bucket for ice or the like, as shown.
